J. A. MOORE

ADVERTISING DEVICE

Filed Dec. 24, 1923

INVENTOR

Joseph A. Moore
By J. J. B. Darlington
his attorney.

UNITED STATES PATENT OFFICE.

JOSEPH A. MOORE, OF PITTSBURGH, PENNSYLVANIA.

ADVERTISING DEVICE.

Application filed December 24, 1923. Serial No. 682,486.

To all whom it may concern:

Be it known that I, JOSEPH A. MOORE, a citizen of the United States, residing at Pittsburgh, in the county of Allegheny and 5 State of Pennsylvania, have invented certain new and useful Improvements in Advertising Devices, of which the following is a specification.

This invention is for an advertising device, and particularly relates to a device of this kind having rotating and stationary parts, with electric lamps or other electric devices carried on the rotatable part.

The present invention has for its principal object to provide a supporting structure on which is a rotatable member and to provide a stationary member at the front of the rotating member, and at the same time provide anti-friction means for supporting the 20 rotating part and transmitting current thereto.

Another object of the invention is to provide an anti-friction support for the rotating member and utilizing such antifriction 25 means to transmit current from the stationary part to the rotating part, whereby the friction of the usual commutator is eliminated, enabling the rotating part to be easily rotated, so that it may be arranged to be rotated from a current of air from a fan or 30 other relatively feeble driving means.

The invention may be readily understood by reference to the accompanying drawings, in which:

35 Fig. 1 is a side elevation of the assembled device;

Fig. 2 is a front view of the device, with the advertising means removed;

40 Fig. 3 is a longitudinal section through the device shown in Fig. 1;

Fig. 4 is a similar section of a slight modification, wherein the parts are vertically arranged, the rotatable part above the support; and

45 Fig. 5 is a view similar to Fig. 4, showing the rotating device below or suspended from the support.

In the drawings, 5 designates a suitably shaped supporting structure of wood or 50 other insulating material having an extension 6 thereon, which is shouldered at 7, the extension preferably being tapered, as indicated at 8, between the body and the shoulder 7. Passing concentrically through the 55 body and the extension, is a metal shaft 9 having a nut 10 threaded on its inner end,

and having its outer end, the end beyond the extension, also threaded.

Mounted on the extension are two sets of ball bearings 11 and 12; one set, 11, being 60 adjacent shoulder 7, and the other set being positioned at the free end of the extension. These bearings carry a hub 13 of wood or other insulating material. A metal connecting plug 14 on the hub contacts with bearing 11 and provides a wire attaching means for one pole of an electric circuit, while a similar connector 15 contacts with bearing 12.

The stationary part of bearing 11 contacts 70 with a metal ferrule 16 in circuit with connector 18 on the support. The stationary part of bearing 12 is electrically connected with shaft 9 through a washer 19, held thereagainst by nut 20, this nut also serving, in 75 conjunction with nut 10, to hold shaft 9 in place. Shaft 9 is connected through conductor 21 with binding post 22. Posts 18 and 22 may be connected with a suitable 80 source of power, and current can be transmitted to electric appliances, such as lamps on the hub.

On the hub, I have shown a plurality of arms 23, on the outer ends of which are electric lamps 24 in circuit with connectors 18 85 and 22 through wires 24^a. The shaft 9, projecting a considerable distance beyond the end of the extension, carries a stationary or other exhibit, around which the lights 24 may revolve. In this way, a stationary 90 center exhibit, without any obstruction at the front thereof and about which the lights revolve, is obtained. Various changes in the particular form of advertising exhibits may be made, those shown being merely illustrative of the invention.

The construction shown in Fig. 4 is, in all respects, similar to that described except that an end thrust bearing 11' has been substituted for the type of ball bearing shown in 100 Fig. 3. This enables the hub to revolve freely in a vertical position, with the supporting member below it.

In the modification shown in Fig. 5, the general arrangement is again similar, but a 105 thrust bearing 12' has been substituted for the bearing 12, enabling the hub to freely revolve when suspended in a vertical position from the support.

Various details of construction and various 110 changes may be made in the construction shown within the contemplation of my in-

vention, and under the scope of the appended claims.

I claim as my invention:

1. In a device of the character described, a supporting member, a shaft projecting from the supporting member, a non-conducting sleeve through which the shaft extends, a pair of spaced apart ball bearings on the sleeve, a hub carried on the bearings, a display member on the hub extending radially therefrom, one of said bearings being joined with a connector and the other bearing being connected to a second connector whereby said bearings may be connected with opposite poles of an electric circuit, electric display means on the said display member in circuit with the respective bearings, and a display device on the end of said shaft in front of the hub.
2. In a device of the character described, a supporting member of insulating material, a hollow extension thereon, a shaft extending through the extension and support and having its forward end projecting beyond

the extension, a pair of spaced apart anti-friction bearings on the extension, one of said bearings being in electrical connection with the shaft, a conductor in circuit with the other bearing, a hub rotatably carried on the bearings, connectors on the hub in circuit with the respective bearings, electric illuminating devices carried by the hub in circuit with said connectors, and a stationary display device carried on the projecting end of said shaft.

3. In a device of the character described, a supporting member, a fixed shaft projecting from the supporting member, a hub on the shaft, an exhibitor carried by the hub, having electric lights thereon, means for transmitting current from the stationary support to the hub, and a fixed disk on the end of the shaft in front of the rotatable hub, the lights on the exhibitor being positioned to rotate about the periphery of the stationary disk.

In testimony whereof I affix my signature.
JOSEPH A. MOORE.
